UNITED STATES PATENT OFFICE.

FRANK DAL LAGO, OF JERSEY CITY, NEW JERSEY, AND JACOB S. JARKOW, OF NEW YORK, N. Y.

DESIGN FOR A HANDKERCHIEF.

Application filed March 21, 1924. Serial No. 9,014. Term of patent 3½ years.

To all whom it may concern:

Be it known that we, FRANK DAL LAGO and JACOB S. JARKOW, both citizens of the United States, and residents, respectively, of Jersey City, in the county of Hudson and State of New Jersey, and the city of New York, borough of Manhattan, in the county and State of New York, have invented a new, original, and ornamental Design for Handkerchief, of which the following is a specification, reference being had to the accompanying drawing, forming part thereof.

The figure is a plan view of a handkerchief, showing our new design.

We claim:

The ornamental design for a handkerchief, as shown.

FRANK DAL LAGO.
JACOB S. JARKOW.
